UNITED STATES PATENT OFFICE

ERNEST S. JOHNSON, OF WEBSTER CITY, IOWA, ASSIGNOR TO KNAPP-MONARCH COMPANY, OF ST. LOUIS, MISSOURI, A CORPORATION OF MISSOURI

INSULATED CONTAINER

Application filed November 13, 1926. Serial No. 148,136.

This invention relates to containers which are adapted to maintain their contents at an unchanging temperature for a considerable period of time after the container is sealed.

5 One of the objects of this invention is to produce a container having a construction which is new in the art and which is by reason of that construction better adapted than its predecessors to maintain the temperature of its contents in an unchanged condition for a long period of time.

Another object of this invention is to produce an insulated container having sealing means which will not readily conduct heat 15 and which will effectively seal the container with unimpaired efficiency regardless of prolonged use of the device.

Another object of this invention is to produce an insulated container having the above 20 advantages and so constructed as to lend itself to a lower cost of production.

Further objects, advantages and capabilities will later appear and are inherently possessed by this invention.

25 My invention further resides in the combination, construction and arrangement of parts illustrated in the accompanying drawing, and while I have shown therein a preferred embodiment of my invention, I wish 30 it understood that the same is susceptible of modification without departing from the spirit of my invention.

Referring now to the drawings, Fig. 1 is a vertical sectional view through the center 35 of the container.

Fig. 2 is a fragmentary view in section showing the manner of attaching the shell to the receptacle.

40 Fig. 3 is a fragmentary view in section illustrating the manner of applying the sealing means and securing the cap to the receptacle.

Fig. 4 is another detail in section showing another manner of attaching the shell to the 45 receptacle and providing threads for the cap on the exterior of the shell.

Fig. 5 is similar to Fig. 4 except that the uppermost portion of the shell has not yet been spun into engagement with a corresponding groove in the receptacle.

Referring now in greater detail to the drawing, a shell generally indicated as 1 surrounding a receptacle 2 is provided with insulating material 3 to prevent the transmission of heat from the receptacle outwardly 55 or from the outside atmosphere inwardly to the receptacle.

There are two manners illustrated for the attachment of the top of the shell to the neck 4 of the receptacle. In Fig. 3 it will 60 be observed that a circumferential bead or projection 5 is provided on the receptacle. This projection may be designed in a continuous circle. The top portion of the container may then be crimped about the bead 65 in the manner illustrated. In Fig. 2 a resilient material 6, such as rubber or other suitable material is illustrated as being interposed between the crimped edge, or spun edge, of the shell in order to effectively seal 70 the joint against the entrance of air or water. This material 6 may be used or not as desired.

In Figs. 4 and 5 another manner of attaching the shell to the receptacle is illustrated. 75 Instead of the projection 5 on the receptacle a depression 7 is provided and a collar, such as a metal collar, is spun into rigid and sealed connection with the depression 7. This collar then may be attached to the top of the 80 shell or it may be, if desirable, continuous and integral with the shell.

A cap generally indicated as 8 is provided and is suited to be attached to the container whether the construction shown in Fig. 3 or 85 Fig. 4 is used. The cap 8 may be provided with threads 9 which will engage the cooperating threads 10 on the receptacle as shown in Fig. 3, or if the construction of Fig. 4 is used, instead of the cooperating threads 10 90 on the receptacle, a cooperating thread 11 will be provided on the shell which surrounds the neck 4 of the receptacle. In either manner, it is plain that the cap may be firmly secured to the container. This 95 cap provides an efficient drinking cup.

In order to provide an efficient means for sealing the open end of the container, I have designed a stopper or heat insulating element generally indicated as 12. This stop- 100

per may be of cellular construction having a single cell or a plurality of cells and may or may not contain heat insulating material. It will be observed that the bottom surface 13 of this stopper is substantially spaced apart from the top surface 14 of the stopper in order to provide sufficient room for an adequate heat insulating means. This stopper is provided with a reduced portion 15 which may be constructed in the manner illustrated or in any other suitable manner. In order to effect the sealing of the open end of the receptacle, this reduced portion 15 is interposed between a shoulder 16 on the cap and the open end of the receptacle. When the cap is screwed down this portion will be forced against the top of the receptacle and will effectively seal it. If desired, a resilient material 17, such as rubber, cork or other suitable material, may be interposed adjacent to the reduced portion 15 in order to aid in sealing the opening of the receptacle.

The cap and the stopper are so designed as to contact with each other only near the periphery of the stopper as is illustrated in Figs. 1 and 3. A considerable space is left between the top surface 14 of the stopper and the top 18 of the cap 8. This space will prevent conduction of heat from the stopper to the cap. In prior constructions which have employed stoppers and caps the central portion of the stopper and the central portion of the cap are ordinarily in contact, the cap thus operating to force the stopper into sealing engagement with the receptacle.

The manner in which I attach my shell to the receptacle very effectively retains the receptacle in its proper position within the shell and at the same time seals the joint effectively.

The manner in which the cap and the stopper cooperate results in the cap exerting its pressure only on the reduced and solid portion of the stopper at the point where both the stopper and the cap are most strong. It can be seen that this combination of cap and stopper is perfectly adapted to long life, whereas if the cap pressed upon the stopper at or near the center of both, one of them or both of them would in time become distorted and the sealing apparatus would then be rendered less efficient and perhaps entirely ineffective.

Having thus described my invention, I claim:

1. An insulated container comprising an inner receptacle having a neck, an outer shell generally spaced apart from the receptacle, heat insulating material disposed between the receptacle and shell, a circumferential projection on the neck of the receptacle, an extension on said shell cooperating with said projection to rigidly connect the shell and receptacle and a cap adapted to fit over said extension.

2. An insulated container comprising an inner receptacle having a reduced neck portion, an outer shell disposed about the receptacle and having an extension engaged with said neck, means connected with said receptacle for rigidly connecting said shell and receptacle and a cap adapted to fit over said connecting means. 70

3. An insulated container comprising an inner receptacle and having a reduced neck portion, an outer shell disposed about the receptacle and having a reduced portion, means connected with said receptacle for rigidly connecting said shell and receptacle and a cap adapted to fit over said connecting means. 75

4. An insulated container comprising an inner receptacle having a neck, an outer shell disposed about the receptacle and having a reduced portion, a circumferential projection on said neck engaged with said portion for 85 effecting a sealed and rigid connection between said receptacle and shell and a cap adapted to fit over said connection.

5. An insulated container comprising an inner receptacle having a reduced neck portion, an outer shell disposed about said receptacle and having a reduced portion, correspondingly curved means on said neck and the reduced portion of said receptacle for effecting a sealed and rigid connection between 95 said shell and receptacle and a cap fitting over said connection. 90

6. In an insulated container, a receptacle having a port, a stopper having flanged portions engaging with the margin of said port to seal the receptacle, and a cap provided with a shoulder portion, said shoulder portion being adapted to press downwardly on the flanged portions of the stopper for retaining the stopper in said engagement. 100

7. A container comprising an inner receptacle having a reduced neck portion, an outer receptacle generally spaced apart from the inner receptacle excepting at a point of attachment, and an annular projection on said reduced neck portion snugly engaged with an annular recess on the outer receptacle for securing the two receptacles together. 110

8. In an insulated container, a receptacle having an open end, a cap provided with a peripheral shoulder portion, and a heat insulating element relatively thick at its central portion to provide substantial heat insulating means in said open end and having peripheral flanges adapted to abut said open end, the shoulder of said cap engaging said flanges for sealing said receptacle. 115

In witness whereof, I hereunto subscribe my name to this specification.

ERNEST S. JOHNSON. 120
